ABSTRACT

A new cultivar of *Clematis* plant named 'EviGsy152' that is characterized by its large sized flowers (up to 14 cm in diameter), its flowers that are deep blue-purple in color with contrasting red-purple anthers, its star-shaped flowers, its repeat flowering from May through July and again in September, its floriferous blooming habit with an abundance of flowers, and its high suitability for use in gardens and containers.

3 Drawing Sheets

1

Botanical classification: *Clematis patens X viticella*.
Variety denomination: 'EviGsy152'.

BACKGROUND OF THE INVENTION

The present invention relates to a new and distinct cultivar of *Clematis* of hybrid origin (Patens Group) and will be referred to hereafter by its cultivar name 'EviGsy152'. 'EviGsy152' is grown as an herbaceous climbing plant for use in the landscape or as a flowering potted plant for the terrace.

'EviGsy152' derived from an ongoing breeding program by the Inventor in his nursery in Guernsey, The Channel Islands. The goal of the breeding program is to select new cultivars of *Clematis* with a compact plant habits with an abundance of flowers that are large in size with unique flower colors. 'EviGsy152' was selected as a single unique plant in May of 2019 and arose from a controlled cross made in June of 2014 between unnamed seedlings of *Clematis patens X viticella* from the Inventor's breeding program.

Asexual propagation of the new cultivar was first accomplished by stem cuttings under the direction of the Inventor in Guernsey, The Channel Islands in May of 2019. Asexual propagation by stem cuttings has determined that the characteristics of the new cultivar are stable and are reproduced true to type in successive generations.

SUMMARY OF THE INVENTION

The following traits have been repeatedly observed and represent the characteristics of the new cultivar. These attributes in combination distinguish 'EviGsy152' as a unique cultivar of *Clematis*.

2

1. 'EviGsy152' exhibits large sized flowers (up to 14 cm in diameter).
2. 'EviGsy152' exhibits flowers that are deep blue-purple in color with contrasting red- purple anthers.
3. 'EviGsy152' exhibits star-shaped flowers.
4. 'EviGsy152' exhibits repeat flowering from May through July and again in September.
5. 'EviGsy152' exhibits a floriferous blooming habit with an abundance of flowers.
6. 'EviGsy152' exhibits high suitability for use in gardens and containers.

The female parent of 'EviGsy152' differs from 'EviGsy152' in having flowers with lighter colored sepals. The male parent of 'EviGsy152' differs from 'EviGsy152' in flowers with slightly darker blue-purple tepals and yellow anthers. 'EviGsy152' can be most closely compared to the *Clematis* cultivars 'The President' (not patented) and 'Evipo019' (U.S. Plant Pat. No. 16,069). 'The President' is similar to 'EviGsy152' in sepal and anther color. 'The President' differs from 'EviGsy152' in having a less compact plant habit, a less floriferous blooming habit, and foliage that becomes flushed with a red-brown coloration. 'Evipo019' is similar to 'EviGsy152' in having a compact plant habit. 'Evipo019' differs from 'EviGsy152' in having flowers with tepals that are lighter in color and a slightly taller plant height.

**STATEMENT REGARDING PRIOR
DISCLOSURES BY THE INVENTOR**

The Applicant asserts that no publications or advertisements relating to sales, offers for sale, or public distribution

occurred more than one year prior to the effective filing date of this application. Any information about the claimed plant would have been obtained from a direct or indirect disclosure from the Inventor. The Applicant claims a prior art exemption under 35 U.S.C. 102(b)(1) for disclosures and/or sales that fall within a one-year grace period to the filing date. Disclosures include website listings by Raymond Evi-
5 son *Clematis* Donahue's Greenhouse, Horticulture Week, GTN Extra, Commercial Horticulture Association, Garden-
10 forum, Plantago, Weibo, Bluestone Perennials, BPnieuws, Wildon Brothers Gardens, Gardens of the world, Le Rose di Firenze, Hayloft Plants, ForalDaily, and Griffin Greenhouse Supplies.

BRIEF DESCRIPTION OF THE DRAWINGS

The accompanying color photographs illustrate the over-
all appearance and distinct characteristics of the new *Clema-
tis*. The photographs were taken of 2.5-year-old plants of
20 'EviGsy152' as grown in a 17-cm container in Guernsey,
The Channel Islands.

The photograph in FIG. 1 provides a view of a plant of
'EviGsy152' in bloom.

The photograph in FIG. 2 provides a close-up view of a
25 flower of 'EviGsy152'.

The photograph in FIG. 3 provides a close-up view of a
leaf of 'EviGsy152'.

The colors in the photographs are as close as possible with
the digital photography techniques available, the color val-
30 ues cited in the detailed botanical description accurately
describe the colors of the new *Clematis*.

DETAILED BOTANICAL DESCRIPTION

The following is a detailed description of 2.5-year-old
plants of 'EviGsy152' as grown in 17-cm containers in
Guernsey, The Channel Islands. The phenotype of the new
cultivar may vary with variations in environmental, climatic,
and cultural conditions, as it has not been tested under all
possible environmental conditions. The color determination
is in accordance with The 2015 Colour Chart of The Royal
Horticultural Society, London, England, except where general
color terms of ordinary dictionary significance are used.
45 General description:

Blooming period.—Blooms from May through July
and reblooms in September in Guernsey, The Chan-
nel Islands.

Plant type.—Herbaceous woody vine, large flowering
50 *Clematis* that blooms on both old and new wood.

Plant habit.—Climber, stems emerge from base, com-
pact.

Height and spread.—Average of 1.2 m in height and 36
cm in spread as a 2.5 year-old plant grown in a
55 container, seasons growth in the landscape attains 90
to 120 cm in height and 50 to 60 cm in spread.

Cold hardiness.—At least to U.S.D.A. Zone 5.

Diseases.—No susceptibility or resistance to pests and
diseases has been observed.

Root description.—Fleshy.

Propagation.—Softwood cuttings from vegetative
shoots.

Time required for root initiation.—Root initiation takes
3 months, 3 to 4 weeks for roots to appear, another
65 4 to 6 weeks to produce a fully rooted cutting ready

for potting, root development from plug to P7 is 3 to 6 months, 30 weeks for mature plant in a P12 container.

Growth rate.—Moderate.

Plant vigor.—Medium.

Stem description:

Shape.—Round.

Stem color.—Young; 144C, mature; 144C with 187A,
older stems; 200D.

Stem size.—Length from base to flowering portion of
the stem; 49 cm in length, 3 mm in diameter.

Stem surface.—Sparsely pubescent.

Stem strength.—Strong.

Internode length.—Average of 7 cm.

Branching.—Basal branching, average of 3 main
branches.

Foliage description:

Leaf arrangement.—Opposite, ternate.

Leaf division.—Compound.

Leaf attachment.—Petiolate.

Leaf quantity.—10 per stems, 3 leaflets per leaf.

Leaf size.—Average of 13 cm in length and 14 cm in
width.

Leaflet shape.—Ovate.

Leaflet base.—Rounded.

Leaflet apex.—Acute.

Leaflet fragrance.—None.

Leaflet venation.—Palmate, color; young upper and
lower surface 144C, mature upper 137D, mature
lower 144A, mid-rib 137C.

Leaflet margins.—Entire.

Leaflet attachment.—Petiolule.

Leaflet surface.—Upper surface glabrous, lower sur-
face matte.

Leaflet size.—Average of 7 cm in length and 6 cm in
width.

Leaflet color.—Young upper surface; 144B, young
lower surface 144B, mature upper surface 137C,
mature lower surface 137D.

Petioles.—Up to 7 cm in length, 2 mm in width, 145A,
flushed with 183B, sparsely pubescent surface.

Petiolules.—Up to 4 cm in length, 1 to 2 mm in
diameter, 145A, flushed with 183B, sparsely pubes-
cent surface.

Inflorescence description:

Inflorescence type.—Solitary.

Inflorescence arrangement.—Terminal and axillary on
new growth.

Pedicel.—2.5 cm in length, 3 mm in diameter, 145A in
color, glabrous surface, moderate strength.

Bud description.—Ovoid in shape, 3.2 cm in length,
1.3 cm in width, 145C to 145D in color, pubescent
surface.

Flower fragrance.—No

Lastingness of flowers.—Individual flowers last about
10 days, self-cleaning.

Flower quantity.—2 open flowers, 14 buds.

Flower type.—Single, rotate, spreading, star-shaped.

Flower aspect.—Outward, rotate.

Flower size.—Up to 14 cm in width, 3.5 cm in depth.

Tepal number.—8.

Tepal shape.—Broadly elliptic.

Tepal apex.—Acuminate.

Tepal base.—Acute.

Tepal margins.—Entire, very light undulations.

Tepal surface.—Both surfaces glabrous, satiny, matte.
Tepal color.—Young and mature upper surface; 93B,

around mid-rib 93C to 93D, 97C to 97D in the middle extending to apex, and slightly suffused with N81B at the base, young and mature lower surface; 5
 93B, around mid-rib 93C to 93D, midrib 145A, apex 145C to 145D.

Tepal size.—Average of 6 cm in length and 4.8 cm in width.

Tepal arrangement.—Overlapping.

Tepal curvature in longitudinal section.—Moderately reflexed to flat.

Receptacle.—7 mm in depth, 9 mm in width, pubescent surface, round in shape, 144B in color.

Reproductive organs:

Gynoecium.—Pistils; around 70, style; 2 cm in length, 15
 1 mm in diameter, color; 157D, stigma; slightly

superior relative to the length of the filaments and height of the anthers, very small, ovary; 144A.

Androecium.—Stamens; 120 to 150, filaments; 1.2 cm in length, glabrous surface, NN155A, 93B to 93C in color, anthers; 5 mm in length, elongated in shape, 187A to 187B in color, glabrous, pollen was not observed.

Seed.—Seed head; an average of 2.5 cm in length, 3.6 cm in width, shiny hairs, style; plumose at base, color; 144A to 144B and 165A to 165B, seed development was not observed.

It is claimed:

1. A new and distinct cultivar of *Clematis* plant named 'EviGsy152' as herein illustrated and described.
